CHILD'S STROLLER

Charles William Chance, Toronto, Ontario, Canada, assignor of sixteen and two-thirds per cent to James Stuart Buckner, sixteen and two-thirds per cent to John Joseph Smith, sixteen and two-thirds per cent to George Richard Chance, sixteen and two-thirds per cent to Allen Rock Gibson, and sixteen and two-thirds per cent to Gordon Moray Williamson, all of Toronto, Ontario, Canada

Application July 23, 1948, Serial No. 147,728

Term of patent 7 years

(Cl. D14—14)

To all whom it may concern:

Be it known that I, Charles William Chance, a subject of the King of Great Britain, residing in the city of Toronto, in the county of York, in the Province of Ontario, Canada, have invented a new, original, and ornamental Design for a Child's Stroller, of which the following is a specification, reference being had to the accompanying drawings, forming a part thereof.

In the drawings—

Figure 1 is a side elevational view of a child's stroller, showing my new design;

Figure 2 is a front elevation;

Figure 3 is a rear elevation;

Figure 4 is a top plan view.

Figure 5 is a top perspective view.

The characteristic features of my design reside in the portions shown by means of full lines in the drawings.

I claim:

The ornamental design for a child's stroller, as shown and described.

CHARLES WILLIAM CHANCE.
